UNITED STATES PATENT OFFICE

DANIEL S. GUSTIN, OF BLOOMFIELD, NEW JERSEY, ASSIGNOR TO WESTINGHOUSE LAMP COMPANY, A CORPORATION OF PENNSYLVANIA

METHOD OF SEALING-IN

Application filed December 28, 1929. Serial No. 417,106.

This invention relates to the manufacture of electrical devices such as incandescent electric lamps in which a base is secured to a lamp bulb by a mechanical connection between the base and the bulb neck as shown and described in my copending application Serial No. 229,825 filed October 31, 1927 and relates more particularly to a method of shaping a bulb neck to receive a retainer element for securing the bulb and base in fixed relation.

In the manufacture of electrical devices such for example, as incandescent electric lamps it is the practice to provide the lamp with a base in the form of a threaded shell or cap having one end open to receive the end or neck portion of a glass bulb. Bases of the above character have usually been secured to the bulb by means of a quantity of cement which is deposited in the base after which the bulb and base are disposed in the desired relation and the cement is subjected to a baking operation to set the cement and firmly secure the bulb and base in fixed relation.

The above construction has been extensively used but certain disadvantages attend this mode of manufacture since it is time consuming and relatively expensive and involves a heat treating operation.

In my copending application above mentioned I have provided a structure which eliminates the use of cement but at the same time utilizes the standard type of screw shell or base. The structure set forth in the said application includes a split or otherwise resilient collar having a circular outside perimeter and having its central or internal perimeter of non-circular form. The said collar snugly fits the interior surface of the base or shell and the non-circular perimeter grips the bulb neck.

It will be appreciated, however, that in order to obtain the proper gripping action between the non-circular perimeter of the collar and the bulb neck, that the said neck must be formed to a predetermined shape to conform with the formation of the internal perimeter of the collar so that when the base is applied over the collar the latter will be

firmly pressed into contact with the accommodating formation in the bulb neck.

When the collar and base have been disposed in proper relation the said base and collar are secured together by solder or by a brazing operation. One of the lead wires of the lamp may be disposed between the collar and the shell while the other lead wire is secured to the usual bottom contact of the shell or base. In the production of incandescent electric lamps of the mechanically based type above described, it has been found that although satisfactory results may be obtained by forming the depressions in the bulb neck by ordinary methods, better results and greater strength is obtained by performing the bulb shaping operation in accordance with the present method to be hereinafter described.

It is an object of the present invention, therefore, to provide a method of quickly and effectively shaping a bulb neck to receive a retainer member.

Another object of the invention is to provide a method for shaping a bulb neck to receive a retainer member and in attaining a maximum strength at the shaped portion.

Another object of the invention is to provide a method of shaping a bulb neck wherein the material of the shaped portion is of greater thickness than before the shaping operation.

Other objects and advantages of the invention will be more fully understood from the following description together with the accompanying drawings, in which

Fig. 1 is a side elevational view of a holder or head for supporting a lamp mount and a bulb in position for consolidation therewith.

Fig. 2 is a fragmentary view of a head showing a bulb and mount in position with fires for contracting the bulb neck about the flare tube of a mount.

Fig. 3 is a view similar to Fig. 2 but shows the position of softening fires for causing a thickening of the bulb wall above its union with the flare tube, also fires for severing the cullet.

Fig. 4 is a cross sectional view of a portion

of the bulb neck showing the thickened glass after the neck has been shaped.

Fig. 5 is a perspective view of a holder showing jaws for compressing the softened bulb neck to form the same to a predetermined shape.

Fig. 6 is a fragmentary detail cross sectional view showing one of the jaws in contact with the softened glass.

10 Fig. 7 is a side elevational view of a bulb partly broken away and showing the formed neck portion.

Fig. 8 is a view taken on line VIII—VIII in Fig. 7.

15 Fig. 9 is a side elevational view of a bulb partly in section showing an annealing fire also a cut off fire for severing the cullet and shows the severed cullet in dotted lines.

20 Fig. 10 is a view of a bulb partly in section with the cullet removed and an annealing fire indicated in dotted lines.

25 Fig. 11 is a perspective view of a retainer ring or resilient collar employed as a retainer member to secure the base to the bulb neck, and

Fig. 12 is a fragmentary cross sectional view showing a bulb neck and base secured together by a retainer member.

30 In practicing the present method a bulb 10 is employed having a neck portion 11 and a cullet 12 which may be supported in a holder 13 ready for movement over a mount 14, the said mount may comprise a flare tube 15 secured to an arbor 16 at a press 17 in the usual manner. The arbor may be provided with support wires 18 for supporting a filament 19. An exhaust tube 21 may be provided in communication with an outlet 22 for exhausting purposes when the mount has

40 been sealed to a bulb. The flare tube 15 is provided with a flange 23 and in the present method it is desirable to have an appreciable portion of the said flange disposed in a plane transverse to the longitudinal axis 45 of the mount as distinguished from flare tubes as heretofore constructed in which the flange instead of being of a substantial right angle construction, sloped downwardly toward its perimeter.

50 The mount may be disposed in a head 24 by securing the exhaust tube 21 in the usual holder or chuck provided in heads for performing what is termed a sealing-in operation, which in lamp making comprises the 55 fusing of the flange of a flare tube to a bulb neck. The bulb 10 may be moved to position as shown in dotted lines in Fig. 1 so that it rests upon contact surfaces 25 extending inwardly toward the axial line of the head 60 which provides a seat upon which to rest the bulb. Centering jaws or members 26 may be provided to engage the bulb neck and hold the same in concentric relation with respect to the flare tube 15. A head holding 65 a bulb and mount in the manner above de-

scribed may be rotated by suitable mechanism, (not shown), and sharp pointed sealing fires 27 may be directed against the outer surface of the bulb neck adjacent to the perimeter of the flange 23. This operation contracts the bulb neck and fuses it with the said flange shown in Fig. 2.

70 After the neck has been consolidated or united with the flare tube, shaping or softening fires 28 (see Fig. 3) are directed against the bulb neck above the point of consolidation between the bulb and flare. These fires serve to soften an appreciable portion of the glass above the flare and to contract the same at which time the glass accumulates resulting in a thickened portion 29 (see Fig. 4). While the glass is still molten a plurality of shaping jaws 31, 32 and 33 are moved inwardly to shape the bulb neck to triangular form to receive a retainer member or collar 34 as shown in Fig. 11. This collar is in the form of a split ring having an outside cylindrical surface 35 and an interior perimeter comprising three straight surfaces or edges 36, 37 and 38.

80 The jaws 31, 32 and 33 are of substantially the same shape as one of the straight edges of the collar 35 so that when the jaws have 85 pressed the neck of the bulb to the proper depth the straight edges 36, 37 and 38 of the retainer member will be accommodated by the depressions formed and the said edges will seat in the depressions so that the retainer member will snugly fit the shaped portion of the bulb neck and be ready to receive a base 90 95 100 105 110 115 120 125 130

During the operation of shaping the bulb neck by means of the jaws 31, 32 and 33 air under pressure may be directed through passage 30 which communicates with the exhaust tube 21 so that the softened glass is forced firmly against the shaping jaws. After the forming jaws 31, 32 and 33 have pressed and shaped the bulb neck, the cullet 12 may, as shown in Fig. 9, be removed by directing a cut off fire 41 against the cullet at a point below the union between the flare tube and bulb neck at which time air is admitted to the space 41' to aid in breaking away or severing of the glass softened by the cut off fire 41.

An annealing fire 42 may also be employed to anneal the lower portion of the neck below the union before the severing operation has been performed. During the severing operation it has been found desirable to employ one or more air jets 43 for directing a stream of air against the shaped portion of the bulb neck to cool the same. After the cullet has been removed the bulb is ready to be placed in an exhaust machine. After the cullet has been removed an operation termed a "pull-down" is performed, this operation consists in moving the mount relative to the bulb

while the glass portion at the seal is still plastic. In lamp making machines the pull-down is accomplished by a downward movement of the chuck which secures the exhaust tube. The plastic material at the seal is thus worked and internal stresses are removed, means for causing the pull-down are not shown since this feature is well known in the lamp art in connection with the sealing-in 10 operation.

As shown in Fig. 10 a bulb having the neck shaped to receive a retainer member is positioned in an exhaust port 44 of an exhaust machine. When in this position it has been 15 found desirable to direct an annealing fire 45 against the union between the bulb neck and flare tube to remove any internal stresses and prevent subsequent cracks or breaks. When in the exhaust machine the bulb is exhausted 20 and tipped off in the usual manner. When removed from the exhaust machine the bulb is ready to receive a base and a retainer member may then be slipped over the shaped portion of the bulb neck and a base disposed over 25 the retainer member and secured thereto as shown in Fig. 12.

It will be understood that when providing a lamp with a mechanically attached base it is necessary to obtain the greatest amount of 30 strength in the bulb neck since by reason of the mechanical connection a certain amount of stress is applied to the bulb neck during handling or use of the lamp when in operation.

35 By reason of the present invention, therefore, a method is provided in which the bulb neck may not only be shaped but strengthened to such an extent that it provides a rugged structure to meet practical requirements.

The above advantages are attained in a simple and effective manner without any radical departure in the use of lamp making machinery since the method is directed to the 40 working or manipulation of the glass which is accomplished primarily by the arrangement, formation and direction of the glass working fires. Heretofore various types of mechanical bases were produced but owing 45 to the fragile condition of the bulb neck, such structures as had been produced were too delicate for the handling attending lamp manufacture and the use of lamps so that a lamp mechanically based by ordinary methods would break at the shaped portion or 50 rupture in the event that any excessive force was applied as for example when a lamp was screwed into a socket.

The present invention provides a reinforced shaped bulb neck of sufficient strength 55 to resist breakage and has therefore made the mechanical basing of lamps practical.

Although a preferred embodiment of the invention is shown and described herein it is 60 to be understood that modifications may be

made therein without departing from the spirit and scope of the invention as set forth in the appended claims.

What is claimed is:

1. The method of sealing-in and shaping 70 a bulb neck which comprises supporting a bulb with the neck portion thereof disposed about the flared portion of a mount, fusing the neck to said flared portion to reform the material in said neck to provide a greater thickness of wall adjacent to the flared portion and in shaping said thickened portion.

2. The method of sealing-in and shaping 80 a bulb neck which comprises supporting a bulb with the neck portion thereof disposed about the flared portion of a mount, fusing the neck to said flared portion to reform the material in said neck to provide a greater thickness of wall adjacent to the flared portion, admitting fluid under pressure into the 85 bulb neck and in compressing the said thickened portion to a predetermined form.

3. The method of forming a bulb neck to receive a base retainer member which comprises supporting a bulb and mount with the flange of the mount disposed within the bulb neck, heating the bulb neck to cause the wall thereof to contact with the flange, heating the bulb neck above the flange to reduce the 90 diameter thereof and thicken the wall and in forming the thickened wall to receive a retainer member.

4. The method of forming a bulb neck to receive a base retainer member which comprises supporting a bulb and mount with the flange of the mount disposed within the bulb neck, heating the bulb neck to cause the wall thereof to contact with the flange, heating the bulb neck above the flange to reduce the 95 diameter thereof and thicken the wall thereof and in forming the thickened wall to a predetermined shape in transverse cross section.

5. The method of forming a bulb neck to receive a base retainer member which comprises supporting a lamp mount having a flange, disposing a lamp bulb having a cullet over said mount with the bulb neck surrounding the flange, heating to contract and fuse the bulb neck about the flange, rendering 100 plastic a portion of the bulb neck above the flare to contract the same and to reform the material in said portion to provide a greater thickness of wall shaping the thickened portion and severing the cullet.

6. The method of forming a bulb neck to receive a base retainer member which comprises supporting a lamp mount having a glass flange, positioning a bulb about the mount with said flange adjacent to the interior wall of the bulb neck, heating the bulb neck about said flange to contract the same and unite the wall of said neck with the 110 perimeter of said flange, heating said bulb neck above the said union to cause the wall 115 120 125 130

to decrease in diameter and increase in thickness, and in admitting air under pressure into said bulb while shaping the said thickened wall.

5 In testimony whereof, I have hereunto subscribed my name this 20 day of December 1929.

DANIEL S. GUSTIN.
